(57) CLAIM

The ornamental design for a fabric locking shelf, as shown and described.

DESCRIPTION

FIG. 1 is a front perspective view of the fabric locking shelf; FIG. 2 is a right side elevational view of the fabric locking shelf of FIG. 1;

FIG. 3 is a left side elevational view of the fabric locking shelf of FIG. 1;

FIG. 4 is a top plan view of the fabric locking shelf of FIG. 1; FIG. 5 is a bottom plan view of the fabric locking shelf of FIG. 1;

FIG. 6 is rear elevational view of the fabric locking shelf of FIG. 1; and,

FIG. 7 is a front elevational view of the fabric locking shelf of FIG. 1.

The broken lines showing features and stitching is included for the purpose of illustrating environment of the design and forms no part of the claimed design. The breaks shown in FIGS. 1 through 7 are not part of the claimed design and represent that no particular length is claimed.

1 Claim, 4 Drawing Sheets
